UNITED STATES PATENT OFFICE.

HOWARD PARKER AND ORTON B. BROWN, OF BERLIN, NEW HAMPSHIRE, ASSIGNEES
TO BROWN COMPANY, OF PORTLAND, MAINE, A CORPORATION OF MAINE.

METHOD OF TREATING ARTICLES MADE FROM PULP.

Continuation of application Serial No. 162,813, filed April 17, 1917. This application filed October 3, 1921. Serial No. 505,103.

To all whom it may concern:

Be it known that we, HOWARD PARKER and ORTON B. BROWN, citizens of the United States, and residents of Berlin, in the county of Coos, State of New Hampshire, have invented certain new and useful Improvements in the Methods of Treating Articles Made from Pulp, of which the following is a specification.

10 This application is a continuation of our application, Serial No. 162,813, filed April 17, 1917, for method of and apparatus for treating articles made from pulp.

This invention relates particularly to 15 method for impregnating walls of pulp pipes, tubes or similar articles, with a material having certain desired characteristics such, for instance, as water-proofing and electrical insulating qualities.

20 In the accompanying drawings:—

Fig. 1 is a diagrammatic layout, in plan, of the installation of the apparatus,

Fig. 2 is an end view, partly in transverse section, of what is shown in Fig. 1, and

25 Fig. 3 is a detail view showing more or less conventionally the means for governing the temperature of the impregnating material.

This invention has been developed in 30 connection with the treating of articles made of pulp, for instance, pulp pipes or tubes or similar articles. Such a pipe may be formed by winding a sheet of pulp on a mandrel until a wall of sufficient thickness has been 35 formed, then removing the pipe from the mandrel and thoroughly drying it. The pipe must then be treated in such manner as the use to which it is to be put may determine. If used as a conduit for electrical 40 wiring, its walls must be thoroughly impregnated with a di-electric and it must also be waterproof. If it should be used for water pipe it must be thoroughly waterproofed. This invention has to do solely 45 with the treating of the tubes so that they shall be best adapted for the duty for which 50 they are desired, and for convenience of description it will be considered that the pipes are to be impregnated with a special grade 55 of pitch which is di-electric and waterproof.

55 Referring now to the drawings, it will be seen that the complete apparatus comprises a plurality or battery of treating units arranged along each side of a common storage tank *a* into which the melted pitch is pumped

in any suitable manner. Each of the units comprises a charging tank *b* adapted to communicate with the storage tank *a* and a treating tank *c* communicating, as hereinafter described, with the charging tank. The 60 treating tanks are of such size that a large number of pipes can be treated at the same time, these pipes being supported in suitable cages *d*, the top and bottom walls of which are perforated as shown. These cages, with 65 the tubes therein, are adapted to be lowered into and removed from the tanks by a crane or the like. It is of course understood that the covers 10 of the treating tanks are removable, and preferably these covers are somewhat dome shaped so that gases may collect 70 therein.

Positioned in each charging tank is a pump 11 continuously driven by a motor 12 or otherwise. Each pump 11 has an intake 75 13 opening into the charging tank *c* in which it is located, and the discharge end of the pump is connected with a pipe 14 which discharges into the treating tank near its upper end and is so arranged that the material 80 passing out of the pipe is projected substantially tangentially into the tank so as to have an initial circumferential or whirling action. 15 is a pipe leading from a multi-way cock 16 in the pipe 14 to the storage 85 tank *a*. 17 designates a pipe leading from the storage tank to a multi-way cock 18 in the intake of the pump. The fluid passes from the bottom of the treating tank to its charging tank through a large pipe 19. It 90 will be seen that with this arrangement, to charge the treating tank, the valves 16 and 18 are turned so that the pump will draw the treating fluid from the storage tank *a* through the pipe 17 and force it into the 95 treating tank through the pipe 14. After the treating tank has been charged, the valve 18 is turned to shut off the pipe 17 and open the inlet side of the pump directly to the charging tank whereupon the pump provides means for continuously circulating the 100 impregnated material in the treating tank, taking it out of the bottom and returning it to the top. When the treating has been carried to a sufficient extent and it is desired to 105 remove the articles, the valves 16 and 18 may be turned to such positions that the treating material can be pumped out of the charging tank back into the storage tank. By so doing the treating tank can be quickly 110

completely emptied before the cover is taken off and thus any loss of the impregnating material, due to vaporization, is eliminated. It has been found that the best results are obtained by removing the impregnating material from the bottom of the treating tank and introducing it with a whirling action at the top.

It is essential that the treatment of the pulp tubes be carried out substantially at a uniform pressure and that a proper supply of the treating material to the treating tank be maintained so that the tubes will always be covered. To these ends, the bottom of each of the treating tanks is connected to what may be termed a pressure line 22 into which the treating fluid is pumped from the storage tank *a* by a positively acting pressure pump 23; the pump 23 being connected by a pipe 24 to the pressure line. The pressure line, at a point adjacent to that at which the impregnating material is supplied thereto, is provided with a discharge pipe 25 leading back to the storage tank *a*, and in this discharge pipe 25 is a pressure regulator of any suitable type. This pressure regulator may be in the form of a relief valve 26, or similar apparatus, which can be either manually set to maintain the proper pressure in the pressure line, or which may be automatically controlled through suitable devices. Each of the treating tanks is connected to the pressure line by a branch pipe 27 provided with a one-way cock 28 so that any one of the treating tanks may be cut off from the pressure line when the treating tanks are being charged or emptied.

With this arrangement it will be seen that there is a continuous flow of impregnating material through the pressure line and the pressure within this line or pipe and all the treating tanks communicating with this pipe is maintained uniform by the regulating device 26. In the event of excess pressure within the pressure line, the regulator 26 will open allowing more of the fluid to flow back into the storage tank, and, if the pressure falls in the pressure line below a predetermined degree, the pressure regulator 26 will prevent any impregnating material going back into the storage tank until the pressure is again built up. It will be found that the pulp tubes being treated will absorb considerable amounts of the impregnating material but this loss is automatically taken care of by the supply through the pressure line. Also it is found that gases are given off in the treatment of the pulp tubes but these gases which accumulate in the upper parts of the tanks do not disturb the pressure within the treating tanks for they merely force the impregnating material back into the pressure line.

For the purpose of maintaining the impregnating material in a fluid state, the stor-

age tank and each of the treating and charging tanks are heated by steam coils located within them. In the present instance, the heating apparatus within the storage tank comprises an upper and lower header 30, 31, respectively, connected by tubes 32. The upper header is connected by a pipe 33 to the steam supply pipe 34. The heating coils 36, 36' within the treating tanks and charging tanks, respectively, are connected by branch pipes to a common live steam line 35 which in turn is connected to the supply pipe 34. The exhaust steam pipe of the storage tank leads through a condenser drum 38 to a hot water well 39. The coils 36 and 36' of each unit are connected by a pipe 40 to exhaust steam pipes 41. In each of the pipes 40 is a condenser chamber or drum 42.

It is of extreme importance that the temperature in the treating tanks be maintained approximately uniform in order that the impregnating material shall be in the proper state of fluidity to most rapidly enter the wall of a pipe, but at the same time care must be taken that the heat is not sufficiently great to burn the fibers from which the pipe is made up, or cause the wall to split and laminate. For this reason each of the treating tanks is provided with separate means for automatically controlling the temperature of the impregnating material therein, and while this automatic means may be of any suitable kind or type, we have shown it, in the present instance, as being effected by governing the supply of steam to the coils 36, 36', and by controlling the release of the water of condensation from these coils, as follows: Interposed in each of the steam inlet pipes 37 is a valve 43 controlled by variations in the temperature of the impregnating material in the charging tank with which the particular valve 43 is associated. Interposed in each of the exhaust pipes 40 is a valve 44 controlled by variations in the temperature of the water of condensation within the condenser drum or chamber 42 with which the particular valve 44 is associated. In the present instance, the control of the valves 43 and 44 is effected through the temperature regulator shown more particularly in Fig. 3. Positioned within each charging tank is a mercury or ether bulb 50 connected by a conduit 51 to a diaphragm 52 which acts through an adjusting cam 52' upon a valve 53 controlling the passage of air under pressure from the pipe 54 to the pipe 55 which leads to a diaphragm within a casing 46 connected to the valve 43. When the temperature within the treating tank raises beyond a predetermined degree, the mercury within the bulb 50 expands, raises the diaphragm 52, which in turn lifts valve 53 from its seat, allowing the air under pressure to flow through the pipe 55 and depress the diaphragm of the

valve 43, thereby closing this valve so as to cut off the supply of steam to the heating coils 36, 36'. When the temperature falls below the above-mentioned predetermined 5 degree, the valve 53 will be allowed to close and the spring of the valve 43 will cause the latter to open and again allow steam to flow to the heating coils. When the temperature of the water of condensation in the condenser 10 drum 42 falls below a predetermined degree the thermostatic device 58 with which this chamber is provided and which is similar to that indicated at 50, will operate the diaphragm 59 and thereby lower the valve 60 and shut off the flow of air under pressure to the pipe 61 thereby relieving the air pressure on diaphragm connected to the valve 44. The spring of this valve will now cause this valve to open so as to allow the water of 15 condensation to flow out of the condensing drum 42. It will be obvious that as the steam passes through the condensing chamber 42 the temperature thereof will be raised above a predetermined degree and the result 20 is that the valve 60 will be raised into opened position and the air pressure will act on the diaphragm of the valve 44 against the spring thereof to bring the valve 44 to its normal position corresponding to the predetermined 25 temperature at which the device is set. If desired, the temperature of the impregnating material within the storage tank may be controlled by connecting up with the valve 65 and the condenser 38 an arrangement 30 such as is shown in Fig. 3 and which has just been described.

In accordance with the provisions of the patent statutes we have described the principles of operation of our invention together 35 with one embodiment of an apparatus which is admirably adapted for carrying out our improved method of treating, but we desire to have it clearly understood that the apparatus shown is only illustrative and the invention can be carried out by other means.

We claim as our invention:—

1. That improvement in the art of treating articles made from pulp, which consists in constantly agitating the impregnating 50 material in a tank containing the articles by introducing said impregnating material tangentially to said tank, and supplying heat to the tank.

2. That improvement in the art of treating articles made from pulp, which consists in constantly agitating the impregnating material in a tank containing the articles, supplying heat to the tank, and automatically governing the heat supply by variations 55 in the temperature of the impregnating material.

3. That improvement in the art of treating articles made from pulp, which consists in constantly circulating the impregnating 60 material through a tank containing the ar-

ticles to be treated, by removing the impregnating material from the lower end of said tank and reintroducing it at the top of said tank with an initial circular flow.

4. That improvement in the art of treating articles made from pulp, which consists in constantly circulating the impregnating material through a tank containing the articles to be treated, supplying heat to the tank, and automatically governing the heat 70 supply by variations in the temperature of the impregnating material.

5. That improvement in the art of treating articles made from pulp, which consists in introducing the impregnating material 75 substantially tangentially into the tank containing the articles to be treated and at the top thereof, and in removing the impregnating material from the center of the lower end of said tank whereby a maximum 80 swirling movement of the impregnating material is obtained.

6. That improvement in the art of treating articles made from pulp, which consists in constantly agitating the impregnating 85 material in a tank containing the articles, supplying heat to the tank, and maintaining said impregnating material within the tank at a uniform pressure.

7. That improvement in the art of treating articles made from pulp, which consists in constantly agitating the impregnating material in a tank containing the articles, supplying heat to the tank, maintaining the tank in open communication with a supply 90 of impregnating material, and maintaining said supply of impregnating material substantially at a constant pressure.

8. That improvement in the art of treating articles made from pulp which consists in constantly agitating the impregnating 95 material in a tank containing the articles, supplying heat to the tank, automatically governing the heat supply by variations in the temperature of the impregnating material, maintaining said tank in communication 100 with a supply of impregnating material, and automatically maintaining said supply of impregnating material and the tank in communication therewith at uniform pressure.

9. That improvement in the art of treating articles made from pulp, which consists in constantly agitating the impregnating material in a tank containing the articles 115 by taking the impregnating material out of the bottom of the tank and reintroducing it at the top of and tangentially to said tank, supplying heat to said tank, and automatically maintaining said impregnating material substantially at a constant pressure.

10. That improvement in the art of treating articles made from pulp, which consists in constantly agitating the impregnating material in a plurality of tanks, supplying 120

heat to the tanks, automatically governing the heat supply of each tank by variations in the temperature of the impregnating material in the respective tanks, and automatically and simultaneously maintaining the impregnating material in all of said tanks substantially at a uniform pressure.

11. That improvement in the art of treating articles made from pulp, which consists

in agitating the impregnating material contained in a tank while the articles to be treated are immersed therein, and supplying the impregnating material under uniform pressure to said tank to maintain the pressure of the impregnating material within the tank substantially at a uniform pressure.

HOWARD PARKER.
ORTON B. BROWN.
